UNITED STATES PATENT OFFICE

JOHN P. PEARSON AND EDWARD J. ZAHNER, OF LA PORTE, INDIANA, ASSIGNEES TO
METAL DOOR & TRIM COMPANY, OF LA PORTE, INDIANA.

METAL DOOR

Application filed August 9, 1928. Serial No. 298,604.

The invention relates to metal doors, and has for its object to provide a door of this character in which a minimum number of parts and fittings are required so that the door will be of exceedingly simple and sturdy construction, and adapted to large volume production.

A further object is to provide a door of this character having integrally formed the panel, 10 the rails, and the rail moldings thereof.

A further object is to provide a door of this character having integrally formed the stiles and stile moldings thereof.

A further object is to provide a door of this 15 character having suitable reinforcing means, and suitable means for securing together the parts making up the door.

A further object is to provide, in a door of this character, a panel having projecting 20 flanges, and channelled members carried by the stiles into which said panel projections are adapted to fit to secure the proper positioning of the parts of the door.

With the above and other objects in view, 25 the invention resides in the combination and arrangement of parts as hereinafter set forth, shown in the drawings, described and claimed, it being understood that changes in the precise embodiment of the invention may 30 be made within the scope of what is claimed without departing from the spirit of the invention.

In the drawings:

Figure 1 is a view of the door in elevation. 35 Figure 2 is a vertical sectional view taken on line 2-2 of Figure 1.

Figure 3 is a horizontal sectional view taken on line 3-3 of Figure 1.

Figure 4 is a fragmentary perspective view 40 of the door showing the manner in which the parts are secured together.

Figure 5 is a view of the member forming the panel, rails and rail moldings shown in elevation.

Figure 6 shows a side view of the same member.

Figure 7 shows a modified structure.

The construction of the door as shown in the drawings comprises a panel 2, upper and lower rails 3, and rail moldings 4, all formed

from a single sheet of metal 1. At the opposite sides of the member 1 are disposed single metal members 15, forming the stiles 6 and the stile moldings 7 of the door. Channelled members 13 horizontally disposed at the top and bottom of the door and secured to the rails and stiles thereof serve to hold the parts of the door together.

In the preferred construction of the door, each side of the panel 2, the rails 3 and the rail moldings 4 is separately formed from a single sheet of metal 1, and two of such metal sheets 1, when disposed back to back in spaced registering relation, form the complete panel 2, rails 3 and rail moldings 4 of the door. 45 Each of the metal sheets 1 at the panel portion thereof is provided with a projection 12, the purpose of which will be hereinafter set forth. A cork filler 5, or any other filler which is suitable for the purpose, is preferably interposed between the metal sheets 1 at the panel portion thereof. This filler 5 tends to keep the metal sheets 1 in proper spaced relation, and to prevent accidental bulging and bending of the panel. The filler 70 also serves to deaden the hollow or drumming sound which ordinarily results when a hollow metal structure is subjected to shock or jar.

Disposed at the opposite sides of the metal sheets 1 are metal members 15, each of which forms a stile 6 and a stile molding 7 of the door. Also formed in each of the members 15 are two channel members 10 which comprise the inwardly bent shoulders 16, the inwardly bent off-set legs 8, the outwardly bent legs 9, and the shoulder members 17 at the outer ends of the legs 9. The shoulder members 17 engage each other and are spot welded together at 11 to form a firm and sturdy construction of the members 15. The channel members 10 so formed, serve to receive the panel projections 12 which are held in the channel members by the gripping action of the shoulder 16 and the leg 9 of the channel, and in being so held the metal members 1 are disposed in correct position with respect to the members 15 and thereby also prevent rattling between the parts.

Channel members 13 are secured at the top and bottom of the door, preferably by spot 100

welding as at 14, and form means for securing the parts of the door together. The channel members 13 also form means for keeping the parts of the door in proper spaced relation, and means for reinforcing the structure of the door. When the parts of the door have been secured together by the use of the channel members 13, the joints of the door are filled in the customary manner, and the door may be grained and finished to represent different woods, or in plain colors, as in the manner well understood in the art.

From the foregoing it will be seen that a metal door is provided constructed from a minimum number of parts, preferably having the panel, rails and rail moldings integrally formed, and the stiles and stile moldings integrally formed; thereby greatly reducing the parts necessary to form, handle and assemble, thus lowering the cost of production, as well as lessening the number of joints present in doors made under the present practice, and thereby diminishing the time and labor cost of filling such joints.

Moreover, owing to the small number of parts and joints, the liability of such becoming loosened by continuous jarring to which a door is subjected is greatly diminished. Also provided are simple reinforcing and securing means for holding the parts of the door together, the whole providing a door well adapted to quantity production and of exceedingly simple and sturdy construction.

While the foregoing is the preferred construction of the door, it is to be understood that many variations may be obviously and easily made, such as the obvious change of forming the member 1 to have only a panel and rails, eliminating the rail moldings to produce a less ornate structure.

The invention having been set forth, what is claimed as new and useful is:

1. In a metallic door, spaced members each forming one side of the panel, rails and rail moldings thereof, lateral extensions projecting from the panel portions of said members, stile members having stile moldings integrally formed therewith, and inwardly directed channel members integrally formed with said stile and stile molding and adapted to receive said extensions, said channels having inwardly directed shoulders formed therein adjacent the outer ends thereof, said shoulders being sprung by insertion of said extensions in said channels and acting to constrictively hold said extensions therein.

2. In a metallic door, registering spaced members each forming one side of the panel and rails thereof, lateral extensions projecting from the panel portions of said members, stile members, and channel members adapted to receive said extensions, said channel members being integrally formed with said stile members and having inwardly directed shoulders formed therein, said shoulders be-

ing sprung by insertion of said extensions in said channels and acting to constrictively hold said extensions therein.

3. In a metallic door, registering spaced members each forming one side of the panel and rails thereof, lateral extensions projecting from the panel portions of said members, stile members, and channel members integrally formed with said stile members, one leg of each channel member having an inwardly directed shoulder formed therein adjacent the outer end thereof, said channel members being adapted to receive and constrictively engage said extensions therein.

In testimony whereof we affix our signatures.

JOHN P. PEARSON.
EDWARD J. ZAHNER.
